UNITED STATES PATENT OFFICE.

MARTIN S. BENNETT, OF MINNEAPOLIS, KANSAS.

LOCK FOR EGG-CRATE TOPS.

1,216,401.

Specification of Letters Patent. Patented Feb. 20, 1917.

Application filed June 5, 1916. Serial No. 101,808.

To all whom it may concern:

Be it known that I, MARTIN S. BENNETT, a citizen of the United States, residing at Minneapolis, in the county of Ottawa and 5 State of Kansas, have invented certain new and useful Improvements in Locks for Egg-Crate Tops; and I do declare the following to be a full, clear, and exact description of 10 the invention, such as will enable others skilled in the art to which it appertains to 15 make and use the same.

My invention has for its object to provide a simple and inexpensive locking means for a vertically adjustable receptacle closure 15 such as those used on egg crates, the improved lock affording means for carrying the crate or the like from place to place.

With the foregoing general object in view, the invention resides in the unique features 20 of construction hereinafter fully described and claimed and shown in the drawings wherein:

Figure 1 is a vertical section of an egg 25 crate showing the improved lock applied to the cover thereof;

Fig. 2 is a horizontal section taken substantially on the plane of the line 2—2 of Fig. 1, showing the lock in operative position;

Fig. 3 is a top plan view of the cover with the lock released; and,

Fig. 4 is a perspective view of a portion of the cover and the lock thereon.

In specifically describing the structure 35 shown in the drawings above briefly described, similar characters will be employed to designate corresponding parts throughout the several views and reference will be herein made to the numerous elements by 40 their respective indices. To this end the numeral 1 designates an egg crate open at its top, two of the opposed sides 2 of said crate having metal strips 3 secured to their inner sides, said strips being bent outwardly 45 and downwardly over the upper edges of the sides 2 and around molding strips 4 which surround the upper end of the crate. At vertically spaced intervals the strips 3 are formed with apertures 5 adapted to receive 50 locking bolts of a vertically adjustable top 6.

The top 6 is received slidably in the crate 1 and is provided on the upper side of two of its edges with reinforcing cleats 7, such cleats having transverse grooves 8 in their 55 lower sides in which a pair of alined wire locking bolts 9 are slidably mounted, said

bolts being adapted to have their outer ends forced into the openings 5 to lock the tops 6 in adjusted position. Preferably the sides 2 of the crate have openings 10 registering 60 with said openings 5 in order that the bolts may be projected through the latter sufficiently to be more effective than would otherwise be possible.

The inner ends of the two bolts 9 are bent 65 upwardly at right angles as indicated at 11 and are received in a pair of apertures 12 formed through a horizontal sheet metal bar 13, said bar being pivoted at its center to the center of the top 6 upon an upright bolt 70 or the like 14. It will thus be seen that by turning the bar 13 horizontally the bolts 9 may be projected and retracted at will. The opposite ends of bar 13 are bent upwardly at 75 right angles as shown at 15 and a hand hold 16 extends between said ends above the body of said bar, said hand hold being secured in place by a rod 17 extending therethrough and having its ends upset in the ends 15. By this construction the hand hold 16 serves 80 as means for turning the bar 13 to project and retract the bolts 9 and at the same time constitutes a handle by means of which the entire crate may be carried from place to place regardless of the position of the top 6. 85

Used in conjunction with the parts above described is a pair of resilient locking fingers 20 one end of said fingers lying on and being secured to the upper side of the top 6 while the intermediate portions of said 90 fingers are bent upwardly at 21 to provide stop shoulders against which the edges of the bar 13 are adapted to strike when turned to either limit of its movement. After forming the shoulders 21 the fingers 20 extend 95 horizontally at 22 to overlie the bar 13 when it is positioned to project the bolts 9, the free ends of said fingers being bent downwardly and then upwardly as indicated at 23 to provide keepers to yieldably 100 retain bar 13 in the last mentioned position. These keepers are so shaped, however, as to permit the bar 15 to be turned to retract the bolts when suitable force is exerted on the hand hold 16. They also serve 105 to prevent upward bending of the ends of the horizontal portion of the strip 13, this strip being formed of rather thin sheet metal for the sake of inexpensive manufacture.

From the foregoing taken in connection with the accompanying drawings, the con-

struction, manner of operation and advantages of the improved crate top will be readily understood without requiring a more extended explanation, but in conclusion I 5 will state that although certain specific details of construction have been shown and described, for accomplishing probably the best results, numerous changes may be made within the scope of the invention as claimed 10 without sacrificing any of the advantages thereof.

I claim:

In combination, a receptacle cover, a sheet metal strip bent into U-shape and pivoted 15 centrally between its ends to said cover, said strip having openings spaced in opposite directions from its pivot, a pair of oppositely extending horizontal locking bolts resting slidably on the cover and having 20 their inner ends received beneath said strip

and bent upwardly into the openings thereof to pivotally connect said bar and bolts, a hand hold extending between the ends of said strip for turning the same to project and retract the bolts and for carrying the 25 cover and receptacle to which it is attached, and a pair of spring fingers secured to said cover and adapted to overlie the horizontal portion of said strip to prevent accidental turning thereof from its normal position 30 and to prevent upward bending of said portion on opposite sides of the pivot.

In testimony whereof I have hereunto set my hand in the presence of two subscribing witnesses.

MARTIN S. BENNETT.
